UNITED STATES PATENT OFFICE.

WILLIAM O. GARNER, OF OBERLIN, AND CHARLES F. LAGANKE, OF CLEVELAND, OHIO; SAID LAGANKE ASSIGNOR TO ZELOTA M. GARNER, OF OBERLIN, OHIO.

TYPE-WRITING MACHINE.

SPECIFICATION forming part of Letters Patent No. 375,062, dated December 20, 1887.

Application filed July 26, 1886. Serial No. 209,162. (No model.)

To all whom it may concern:

Be it known that we, WILLIAM O. GARNER, of Oberlin, in the county of Lorain and State of Ohio, and CHARLES F. LAGANKE, of Cleveland, in the county of Cuyahoga and State of Ohio, have invented a certain new and Improved Type-Writing Machine; and we do hereby declare that the following is a full, clear, and complete description thereof.

10 Our invention is an improvement in the class of type-writer in which a movable type-plate is used with a finder-arm, which is provided with a pin or projection to engage apertures or openings in an index-plate, the index-plate and the type-plate being so constructed relatively to each other that when the pin of the finder-arm engages an opening in the index-plate the corresponding letter on the type-plate is brought into the proper position to be impressed upon the paper, and has for its object increased speed in writing by printing whole words of two, three, or four letters each at one impression instead of printing them letter by letter. This is accomplished by increasing the size of the index and type plates and certain changes in the construction to enable the type carrying or feed mechanism to be automatically changed to correspond with the change from a single letter to a word of two, three, four, or more letters.

30

One form of our invention is shown in the accompanying drawings, and the invention is fully set forth in the following specification and claims.

35 In the drawings, Figure 1 is a plan view of a Hall type-writer with our improvements attached. Fig. 2 is a section of the carriage on the dotted line *y y* in Fig. 1, with the top plate turned back and shown in elevation. Fig. 3 is a front side view of the carriage. Fig. 4 is a plan view of the carriage with the top plate turned backward and shown in section. Fig. 5 is a vertical sectional view on line *x x*, Fig. 45 1. Figs. 6, 7, 8, and 9 are detail views, to which reference will be made hereinafter.

Like reference-figures are used in the drawings to indicate like parts.

The main parts of the type-writer—the frame,

the carriage, the inking-pad, paper-holder, printing-post, and finder-arm—are all substantially the same as those shown and described in the patent to Hall, No. 238,387. The type-plate is enlarged and provided with a certain number of rows of type—letters and numerals—running lengthwise of the machine. Next these rows of type are one or more rows of words of two letters most commonly used, such as “on,” “to,” “it,” “is,” “us,” “as,” &c. Next to these are one or more rows of type of words of three letters of general use, such as “and,” “are,” “the,” “you,” “Sir,” &c. Next to these are one or more rows of type for words of four letters in most common use, as “into,” “your,” “were,” “ever,” “thus,” &c.

55 The number of words may be varied according to the size of the plate and limited to such number as may be found by experience to give best results.

70 The index-plate is made of a size to correspond to the type-plate, and is provided with suitable holes to receive the pointer of the finder-arm to give the proper impression of letter or word in the usual manner of a Hall type-writer.

75 It will be evident that as the words occupy more space than the single letters it is necessary to provide some means for giving the carriage the proper movement in respect to the paper. We accomplish this by the following means: The feeding of the carriage is effected in the common way by a spring acting upon a pinion, a rack engaged by the pinion, and a releasing mechanism which engages the rack and automatically releases the carriage and permits the spring to move it the requisite distance. This is accomplished by levers 29 and 31 and spring-arm 32. The two former are of the same construction as those heretofore used. The latter is, however, of slightly different construction. The levers 29 and 31 are pivoted upon stud 30. Upon this stud is mounted a pinion, 34, provided with an inwardly-extending hub. This hub is provided with notches of different depths. If the type-plate has single letters and words of two, three, and four letters each, there will be four notches in the

hub of the pinion. The spring-arm 32 has an opening, 44, through it, in which there is the projection 45. When placed in operative position, the hub extends within the opening in the spring-arm and the latter, when released from engagement with the rack 6 by the movement of the parts required to make an impression on the paper, springs outward as far as the notch engaged by the projection 45 of the arm will permit. Below the pinion is a bar, 35, having a racked portion gearing with pinion 34. The racked portion is supported in engagement with the pinion by the bracket *a*, which is provided on top with a groove to receive the same. The forward end of the bar 35 passes through and slides in a bracket, *b*, near the front of the machine. Near the front of the machine the bar 35 is provided with the upwardly-extending stud 50^a.

20 The finder-arm 38 is, as heretofore, pivoted to a flat bar extending forward from the type-plate frame, and to this bar is rigidly attached a slotted arm, 37, extending toward bar 35, and has its slot engaging the stud 50^a thereon.

25 The slot is of a little greater length than the type and index plates, so that in moving the arm from one side of the plate to the other in a straight line the stud 50^a will not come in contact with the ends of the said slot. In 30 moving the finder-arm from one row of holes in the index-plate to another the arm 37 will move the rack and cause the pinion 34 to turn. When the pointer of the finder-arm is engaged with any of the holes in the rows for single 35 letters and numerals, the projection 45 is opposite the notch 43^a of the hub of the pinion, so that when released it will spring outward but a short distance and be arrested in such position as to engage the rack-bar 6 one groove 40 in advance and permit the forward movement of the carriage only the space of a single letter. When, however, the finder-arm is drawn forward and the pointer of the same made to engage one of the holes of the rows for words 45 of two letters, the hub of the pinion is turned so that the projection 45 will be opposite notch 43, and, this notch being of double the depth of 43^a, on being released the spring-arm will spring outward a farther distance and be arrested in position to engage the rack-bar two grooves in advance. In like manner, when the 50 pointer-arm is in position to print a word of three letters, the pinion is turned to bring the hub in such a position as to bring the notch 55 42 opposite the projection 45 of the spring-arm, and when the finder-arm is so placed as to print a word of four letters the pinion is placed so that notch 41 comes opposite the said projection. These notches being of the proper 60 depths to permit the spring-arm to engage the rack-bar three and four grooves in advance, the required amount of movement to the carriage, when printing words of three and four letters each, is secured. The construction of

the hub of the pinion and the notches therein 65 are best shown in Fig. 8.

When it is desired to raise the top plate of the machine, the slotted arm must be disengaged from the stud 50^a.

It is sometimes desired to move the carriage 70 without printing. This is accomplished in much the same manner as in the class of type-writers referred to, only that with our construction this can be done with much greater rapidity, as by leaving the pointer of the finder-arm between two of the holes for words of three or four letters a pressure upon the finger-piece 49 will move the carriage three or four grooves of the rack-bar. The finger-piece 49 is pivoted to the lever 29 and is held, when 80 desired, in an operative position by a spring-catch, 50. (See Fig. 9.) The return of the carriage to begin another line is accomplished by grasping the thumb-pieces 51 and 52 on levers 29 and 31, as has been done heretofore. 85

The other parts not herein described are the same as those of the type-writers hereinbefore referred to.

What we claim, and desire to secure by Letters Patent, is—

1. The combination, with the movable type-plate of a type-writer, having type for single letters and type for words of more than a single letter thereon, and the feeding devices, of a variable stop for the spring-arm of the feeding devices, and a connection, substantially as described, between said variable stop and the type-plate, whereby the movement of the spring-arm is controlled by the position of the type-plate, substantially as set forth. 90

2. The combination, with the movable type-plate of a type-writer, having type for single letters and type for words of more than a single letter, of a pinion provided with stops of different lengths for the spring-arm of the feeding devices, a rack engaging said pinion, and a connection between the rack and type-plate, substantially as described. 100

3. The combination, with the movable type-plate of a type-writer, having type for single letters and type for words of more than a single letter in rows thereon, of a pinion provided with stops of different lengths for the spring-arm of the feeding devices, a bar provided with a rack engaging said pinion, having 110 a stud thereon, and a slotted arm rigidly connected with the forward-extending bar, attached to the frame of the type-plate, and having its slot engaging the stud on the said rack-bar, substantially as described. 115

In testimony whereof we affix our signatures in presence of two witnesses.

WILLIAM O. GARNER.
CHARLES F. LAGANKE.
